US0D1052749S

(12) **United States Design Patent** (10) **Patent No.:** **US D1,052,749 S**
(45) **Date of Patent:** **** Nov. 26, 2024**

(54) **ATTACHMENT FOR MASSAGE DEVICE**

(71) Applicant: **Therabody, Inc.**, Los Angeles, CA (US)

(72) Inventors: **Jason Wersland**, Los Angeles, CA (US); **Benjamin Nazarian**, Beverly Hills, CA (US); **Jaime Sanchez Solana**, Los Angeles, CA (US); **Danny Zeng**, Shenzhen (CN); **Yano Pang**, Shenzhen (CN); **Sunny Wang**, Dongguan (CN)

(73) Assignee: **Therabody, Inc.**, Los Angeles, CA (US)

(**) Term: **15 Years**

(21) Appl. No.: **29/910,772**

(22) Filed: **Aug. 24, 2023**

(51) **LOC (14) Cl.** **24-01**

(52) **U.S. Cl.**

USPC **D24/215**

(58) **Field of Classification Search**

USPC D24/215, 200, 211, 212, 213, 214, 133, D24/107, 231
CPC A61H 7/00; A61H 7/002; A61H 7/003; A61H 7/004; A61H 7/005; A61H 15/00; A61H 2015/0007; A61H 2015/0014; A61H 2015/0042; A61H 23/00; A61H 2023/002

(57) **CLAIM**

The ornamental design for an attachment for massage device as shown and described.

DESCRIPTION

FIG. 1 is a top front isometric view of an attachment for massage device showing the claimed design;

FIG. 2 is a bottom front isometric view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

1 Claim, 4 Drawing Sheets
